Primary Examiner — Antoine Duval Davis(74) *Attorney, Agent, or Firm* — Wolf, Greenfield & Sacks, P.C.(57) **CLAIM**

The ornamental design for a sensor device, as shown and described.

DESCRIPTION

FIG. 1 is a bottom, front, left side perspective view of a sensor device showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a bottom plan view thereof; and,

FIG. 7 is a top plan view thereof.

All broken lines illustrate portions of the sensor device that form no part of the claimed design.
